Primary Examiner — Abraham Bahta*(74) Attorney, Agent, or Firm* — Toohey Law Group, LLC(57) **CLAIM**

The ornamental design for a cargo container, as shown and described.

DESCRIPTION

FIG. 1 is a back, top, and left side perspective view of the cargo container, showing the new design;

FIG. 2 is a top plan view thereof;

FIG. 3 is a bottom plan view thereof;

FIG. 4 is a left side view thereof;

FIG. 5 is a right side view thereof;

FIG. 6 is a front side view thereof; and,

FIG. 7 is a rear side view thereof.

The ornamental design which is claimed is shown in solid lines in the drawings. Any broken lines depict portions of the cargo container that form no part of the claimed design.

1 Claim, 7 Drawing Sheets(56)
